UNITED STATES PATENT OFFICE

100,300

DESIGN FOR A MOLDED CONFECTION

Conrad Spoehr, Chicago, Ill.

Application February 24, 1936, Serial No. 61,316

Term of patent 14 years

To all whom it may concern:

Be it known that I, Conrad Spoehr, a citizen of the United States, residing at 1439 Fargo Avenue, Chicago, in the county of Cook and State of Illinois, United States of America, have invented a new, original, and ornamental Design for a Molded Confection, of which the following is a specification, reference being had to the accompanying drawing, forming a part thereof.

Fig. 1 is a plan view of a molded confection showing my new design.

Fig. 2 is a cross sectional view along the lines 2—2 on Fig. 1.

I claim:

The ornamental design for a molded confection as shown.

CONRAD SPOEHR.
